John F. Noeau

UNITED STATES PATENT OFFICE.

CHARLES W. VAN VLEET, OF KINGSTON, NEW YORK, ASSIGNOR OF ONE-THIRD TO
ROBERT C. RIDDICK, OF KINGSTON, NEW YORK, AND ONE-THIRD TO CHARLOTTE
A. MAXWELL, OF SAUGERTIES, NEW YORK.

PROJECTILE-THROWING DEVICE FOR GAME APPARATUS.

1,382,696.

Specification of Letters Patent. Patented June 28, 1921.

Original application filed January 5, 1920, Serial No. 349,409. Divided and this application filed May 22, 1920. Serial No. 383,382.

To all whom it may concern:

Be it known that I, CHARLES W. VAN VLEET, a citizen of the United States, and resident of Kingston, in the county of Ulster 5 and State of New York, have invented certain new and useful Improvements in Projectile-Throwing Devices for Game Apparatus, of which the following is a specification.

10 This application for patent is a division of my pending application Serial No. 349,409, filed January 5th, 1920, for game apparatus.

15 The subject of the present case is a projectile-throwing device of simple and efficient construction and operation for use more especially as an element of a game apparatus comprising a board and movable game-pieces; said device being adapted to 20 be mounted on or adjacent the board and to be manipulated by a player in such a manner as to throw a projectile toward and against a target or game-piece located on the board.

25 The preferred form of embodiment of my invention herein illustrated comprises a suitable base, a member pivoted thereon having an upwardly-projecting arm bearing a projectile holder, and also having a depending tail-piece, and a trigger pivoted on said base and having an arm provided with a part adapted to be detachably engaged and held by the tail-piece, whereby when the trigger is manually actuated the said tail-piece is 30 quickly raised and the socket bearing arm is force thrown forward in a manner to shoot the projectile from the holder and toward a target or game-piece, as determined by the aim of the player, as will be herein- 35 after more fully described. The precise scope of the invention will be defined in the appended claim.

In the drawings—

Figure 1 is a plan of a projectile-throwing 45 device embodying my invention, said device being illustrated as pivotally mounted on a game-board; a part of which latter is shown.

Fig. 2 is a sectional elevation of the said device and the adjacent portion of the game-board.

50 Referring to the drawings, 10 designates a portion of a game-board with which movable game-pieces are employed, such, for ex-

ample, as described in my pending application Serial No. 349,409 aforesaid. My improved projectile-throwing device is illustrated as mounted at the front of the board, the adjacent wall of which, in the present instance, is indented and formed in semblance of a fort, as at 18. The construction 60 of the device is such that it may be trained to throw a projectile at a game-piece wherever located on the board. Said device, in its preferred form, comprises a base plate 19 having at one end an upstanding pindle 65 20 adapted to be pivotally supported in a vertically-perforated lug 21 at the front of the board, so that the base plate and its appurtenances may be swung horizontally 70 to various angular positions with relation to the board, at the will of the player. On this plate are formed, in spaced relation to each other, two pairs of lugs 22, 29, respectively, between the former of which, adjacent the pivot 20, is pivoted a vibratory 75 member 23 having a depending tail-piece 24 and an upwardly and outwardly extending arm 25. This arm bears at its free end a projectile holder constituted by a tubular socket-piece 26 adapted to receive a pellet, 80 as 17. The tail-piece 24 is adapted to be detachably engaged by an upstanding lip 27 on the longer arm 28 of a trigger lever comprising a plate which is pivoted in and between the lugs 29 adjacent the outer end 85 of the base plate. The lip 27 is constituted by the angular bent extremity of the arm 28. The co-operative relation of the parts just described is such that when the lip of the trigger lever is engaged with the tail-piece 24 of the member 23 the latter is held in position with the arm 25 extending outwardly and upwardly and the socket-piece 26 forwardly and upwardly, as clearly indicated 90 in Fig. 2. With the parts thus positioned, if a pellet be inserted in the socket-piece, and the shorter arm 30 of the trigger lever be sharply depressed by pressure of the finger applied thereon, the engaged portion of the member 23 will be quickly raised and the 95 arm 25 be thrown forward in a manner to project the pellet from the socket-piece and toward the target or game-piece, in accordance with the accuracy of the aim of the "gunner." Such aim depends upon the angular relation of the "gun" to the target

and the amount of pressure applied by the player to the trigger; the proper throw and trajectory of the projectile in each case thus requiring a fair amount of skill and furnishing much amusement and entertainment.

I do not limit my invention to the exact details of construction herein disclosed, as the same may be varied within the principle of my invention and the scope of the appended claim.

I claim—

In a projectile throwing device for game apparatus, a base, an upwardly-extending swinging arm pivotally supported at its lower end on said base, a projectile holder on the upper end of the arm, a tail-piece depending angularly from said arm adjacent

the pivot of the latter, and a trigger lever fulcrumed on said base at a point in spaced relation to the pivoted end of the swinging arm, the longer member of said lever extending toward the pivoted end of the arm and terminating in an upstanding angular portion in frictional contact with the lower surface of the said tail-piece, and the shorter member of the lever constituting a finger piece by the actuation of which the longer member imparts an upward swinging movement to the tail-piece and the arm.

Signed at Kingston, in the county of Ulster and State of New York this 6th day of May, A. D. 1920.

CHARLES W. VAN VLEET.
